[57] CLAIM

The ornamental design for a bicycle trailer, as shown and described.

DESCRIPTION

FIG. 1 is a side perspective view of a bicycle trailer showing my new design;

FIG. 2 is a top plan view thereof;

FIG. 3 is a side elevational view thereof, the opposite side being substantially a mirror image of that shown;

FIG. 4 is a front elevational view thereof;

FIG. 5 is a rear elevational view thereof;

FIG. 6 is a bottom plan view thereof;

FIG. 7 is a side elevational view thereof, with the hitch bar in raised condition and the center wheel in lower condition; and,

FIG. 8 is a front elevational view of FIG. 7.

FIG.1.

FIG. 2.

FIG.3.

FIG.4.

FIG.5.

FIG.6.

FIG. 7.

FIG.8.
